US00D592905S

(12) **United States Design Patent**
Pinelli et al.

(10) **Patent No.:** US D592,905 S
(45) **Date of Patent:** ** May 26, 2009

(54) **WATER BOTTLE LID**

(75) Inventors: **Steven N. Pinelli**, Gary, IN (US); **Sami M. El Saden**, Winnetka, IL (US); **Xijin Lai**, Chicago, IL (US); **Brian Clemens**, Burnsville, MN (US)

CLAIM

(58) **Field of Classification Search** D7/387, D7/396.1, 396.2, 391, 900, 397, 510, 511, D7/509, 523, 532, 536, 538, 392, 601, 602, D7/605, 619.1, 622, 600; D11/24; D24/199; D3/202; D9/537, 420, 776, 502, 526, 443, D9/435, 522, 527, 434, 448, 554, 549, 551; 215/200, 387, 11.6, 10; 206/560; 220/387, 220/711, 703, 592.16, 592.17, 495.04, 560; 226/406; 229/400; 383/110

See application file for complete search history.

(56) **References Cited**

We claim the ornamental design for a water bottle lid, as shown and described.

U.S. PATENT DOCUMENTS

2,447,870 A 8/1948 Polcyn
3,059,816 A 10/1962 Goldstein

DESCRIPTION

FIG. 1 is a perspective view of a water bottle lid according to the new design;

FIG. 2 is a left side view of the water bottle lid shown in FIG. 1;

FIG. 3 is a rear view of the water bottle lid shown in FIG. 1; FIG. 4 is a front view of the water bottle lid shown in FIG. 1; FIG. 5 right side view of the water bottle lid shown in FIG. 1; and,

FIG. 6 is a top view of the water bottle lid shown in FIG. 1. Features shown in broken lines in the drawings are not part of the claim.
